Primary Examiner—Ted Shooman*Assistant Examiner*—Nanda Bondade*Attorney, Agent, or Firm*—Emrich & Dithmar[57] **CLAIM**

The ornamental design for a hand held, self contained, personal voice amplifier, as shown and described.

DESCRIPTION

FIG. 1 is a front and left side perspective view of a personal voice amplifier showing my new design;
FIG. 2 is a front elevational view thereof;
FIG. 3 is a right side elevational view thereof with the left elevational view being a mirror image of the right side elevational view;
FIG. 4 is a rear elevational view thereof;
FIG. 5 is a bottom plan view thereof; and,
FIG. 6 is a top plan view thereof.
The broken line showing of the rear panel details is for illustrative purposes only and forms no part of the claimed design.
